UNITED STATES PATENT OFFICE.

HENRY P. GROHN, OF CHICAGO, ILLINOIS, ASSIGNOR TO CHARLES A. SHOEMAKER, OF CHICAGO, ILLINOIS.

TANK-CAR.

1,253,028.

Specification of Letters Patent.

Patented Jan. 8, 1918.

Application filed October 28, 1915. Serial No. 58,334.

To all whom it may concern:

Be it known that I, HENRY P. GROHN, a citizen of the United States, residing at Chicago, in the county of Cook and State of Illinois, have invented a certain new and useful Improvement in Tank-Cars, of which the following is a full, clear, concise, and exact description, reference being had to the accompanying drawings, forming a part of this specification.

My invention relates to tank cars and has for its general object the provision of means whereby the tank is anchored at one end in fixed relation to the underframe and is elsewhere mounted to permit it to move with respect to the underframe at its other end, whereby contraction and expansion of the tank with respect to the underframe is permitted. In the preferred embodiment of the invention the tank is anchored to one body bolster only and is free to move with respect to the other body bolster to permit of expansion and contraction of the tank. In carrying out my invention the tank desirably carries two depending flanges between which a body bolster is embraced so that movement of the tank with respect to the body bolster is prevented. This anchorage of the tank to one of the body bolsters is desirably strengthened by fastening the flanged structure, carried by the tank, to the center sills of the underframe whereby vertical displacement of the tank with respect to the underframe is avoided, though I do not wish to be limited to this supplemental characteristic of the anchorage of the tank to the underframe.

I will explain my invention more fully by reference to the accompanying drawings showing the preferred embodiment thereof and in which Figure 1 is a longitudinal elevation of a tank car constructed in accordance with my invention; Fig. 2 is a perspective view of the preferred form of tank anchoring structure; Fig. 3 is a view on line 3 3 of Fig. 1; Fig. 4 is a view on line 4 4 of Fig. 1; Fig. 5 is a view of a filler block; Fig. 6 is a view on line 6 6 of Fig. 3; Fig. 7 is a bottom view illustrative of the anchoring device, part of the tank being shown also in this figure; and Fig. 8 is a view on line 8 8 of Fig. 3.

Like parts are indicated by similar characters of reference throughout the different figures.

Two main parts of the car structure are the tank 1 and the underframe which is inclusive of the center sills 2 which are supported by body bolsters 3 that in turn are mounted to swing upon truck bolsters 4 that are mounted upon car wheels 5, belonging to wheel trucks at the forward and rear ends of the underframe, the type of underframe illustrated being well known to those skilled in the art but to the employment of which underframe I do not wish to be limited in practising my invention. The body bolsters 3, in the type of underframe illustrated, are of hollow diamond shape and embrace the center sills 2 to which the body bolsters are riveted. The anchorage for the tank is preferably in the form of a casting that includes the tank seat 6 conforming in curvature to the tank and in which the bottom of the tank is received, rivets 7 serving to hold the tank and its anchorage in assembly. The tank seat is provided with laterally projecting wings 8 that are also riveted to the bottom of the tank and which wings are provided for the purpose of enlarging the area of engagement of the tank with its seat. The main portion 6 of the tank seat is provided with pedestals 9 cast integrally with the tank seat, these pedestals being riveted to the top flange of the center sills as indicated at 10. The anchorage casting also includes transversely disposed depending flanges 11 for receiving a portion of the body bolsters therebetween, the body bolster having snug fit in the space between the flanges 11, whereby the tank is prevented from moving longitudinally of the car with respect to the body bolster to which it is anchored. The body bolster illustrated is formed of channel iron and when thus formed I desirably insert a filler block 12 between the tank seat 6 and the body bolster, this filler block being received between the flanges of the upper channel iron of the body bolster. This filler may be riveted to the tank seat and also to the tank itself. The rivets by which the tank is secured to its seat and the seat is secured to the center sills serve to prevent the tank from rising where it is anchored to a body bolster, though an anchoring tank band 13 may also be employed in the neighborhood of this body bolster, if desired. A tank seat is also provided at the other end of the tank car, parts of this tank seat structure that are similar to the tank seat of the

structure before described being given similar characters of reference excepting that such character of reference have prime exponent marks added thereto. The assembly 5 of the second tank seat with the under-frame of the car is effected by the body bolster 3¹ entering between the flanges 11¹ and also by the rivets 10¹ that unite the pedestals 9¹ with the center sills 2. In order to permit 10 the tank to expand and contract the tank is free to slide upon the seat 6¹, being desirably unsecured thereto by rivets in which case the tank band 13¹ would be employed to keep the tank from rising from its 15 seat 6¹.

The additions to the underframe structure which are required by my invention for the purpose of effecting the proper assembly of the tank therewith are reduced to a 20 minimum while at the same time the tank seats take part in maintaining both body bolsters in their proper relation to the center sills, a structure being produced having advantages that will be appreciated by those 25 skilled in the art.

While I have herein shown and particularly described the preferred embodiment

Copies of this patent may be obtained for five cents each, by addressing the "Commissioner of Patents, Washington, D. C."

of my invention I do not wish to be limited to the precise details of construction shown as changes may readily be made without departing from the spirit of my invention, but having thus described my invention I claim as new and desire to secure by Letters Patent the following:—

A tank car structure including wheel 35 trucks at its ends; an underframe having body bolsters swingingly supported upon said trucks; a tank; transverse flanges depending from the bottom of the tank and between which one of said body bolsters 40 is snugly received to prevent longitudinal movement of the tank at said body bolster in both directions; and a seat for the tank at the other end of the car upon which the tank may slide to permit of its expansion 45 and contraction.

In witness whereof, I hereunto subscribe my name this twenty-first day of October, A. D. 1915.

HENRY P. GROHN.
